UNITED STATES PATENT OFFICE.

ROY D. CONWAY, OF CHATHAM, NEW JERSEY, ASSIGNOR TO WESTERN ELECTRIC COMPANY, INCORPORATED, OF NEW YORK, N. Y., A CORPORATION OF NEW YORK.

TELEPHONE SYSTEM.

Application filed December 29, 1919. Serial No. 348,124.

To all whom it may concern:

Be it known that I, Roy D. Conway, a citizen of the United States, residing at Chatham, in the county of Morris and State 5 of New Jersey, have invented certain new and useful Improvements in Telephone Systems, of which the following is a full, clear, concise, and exact description.

This invention relates to an improved 10 method and means for signaling over transmission lines and has particular reference to such method and means as applied to telephone systems.

Toll signaling systems have been devised 15 wherein physical and phantom lines are employed for interconnecting distant offices or subscribers. In such systems, certain of the lines are employed for the transmission of various signals, from one distant office, utilized to signal an operator at the other distant office and to control the operation 20 of telephone repeaters at intermediate offices. This has been accomplished by the transmission of a single impulse 25 upon the insertion of the plug of a link circuit into the jack of any line when initiating a call thereover.

An object of the present invention is to transmit 30 a series of impulses from a central office over a signaling circuit to distant offices to identify at one of the latter offices a particular line which has been taken for use.

Another object is to transmit a series of 35 impulses from a central office over a signaling circuit to operate telephone repeaters at intermediate offices and to transmit another series of impulses to a distant office to identify thereat a particular line which 40 has been taken for use at another distant office.

Another and more specific object is to effect 45 the transmission of each series of impulses simultaneously to the distant and intermediate telephone repeater offices from an impulse sending mechanism arranged centrally with respect to said offices.

A preferred embodiment of the invention 50 is illustrated diagrammatically in Figs. 1 to 4, inclusive, of the accompanying drawings, the figures being arranged from left to right in their numerical order. Fig. 5 is 55 a diagrammatic view of one of the link circuits employed at each terminating end of the circuit.

Briefly, the invention is shown as consisting of two distant offices W and Z, two intermediate telephone repeater offices Y and Y', and a central repeater and impulse sending office X. The apparatus at office Y' 60 being a duplicate of that at office Y with the mechanism reversed with respect to the showing in Fig. 3, it is believed that the conventional illustration of office Y' is sufficient for a clear understanding of the invention. Physical transmission lines A and C and the phantom line B are employed for interconnecting the various offices. Each of the transmission lines has associated therewith at offices X, Y and Y', a telephone repeater of any well known filament control type and since these repeaters form no part of the present invention, the same are only conventionally shown. At the central office X, an impulse sending mechanism is provided, the operation of which is initiated by the insertion of the plug of a link circuit into any one of the jacks at either of the terminating or distant offices. The initial operation of this mechanism transmits 70 a series of impulses to all of the offices simultaneously, the function of which is to render effective the telephone repeaters at offices X, Y and Y'. At the terminating or distant office where the call is initiated, 75 the operator then actuates the ringing key of the link circuit taken for use, whereupon the impulse mechanism is again operated to simultaneously transmit a second series of impulses to all of the offices. This second 80 series of impulses operates groups of stepping relays at all of the offices but has no material effect upon apparatus at the distant office where the call is initiated nor at the repeater offices X, Y, and Y', since the 85 repeaters at the latter offices remain effective as long as a link circuit is connected to one of the transmission lines. However, this second series of impulses operates the mechanism at the other distant office in such 90 manner as to select and operate a signal individual to the line over which the call has been initiated. The operator at said distant office, observing the operated condition of this signal, may establish connection with the other distant office by the insertion of the plug of a link circuit into the jack of the line taken for use.

At the termination of a conversation, the operator at one distant office may transmit 110

- a disconnect signal to the operator at the other distant office by the operation of the ringing key of the link circuit which again causes the transmission of an impulse to the impulse sending mechanism at office X to initiate the operation thereof. This operation of the impulse sending mechanism has the effect of operating a supervisory signal in the link circuit at the other distant office 10 associated with the particular line, whereupon the operator withdraws the plug of said circuit from its jack.

When the link circuits have been disconnected from the jacks of all of the lines, 15 another initiating impulse is transmitted to office X to start the operation of the impulse sending mechanism thereat. The impulses now transmitted to the various offices operate the apparatus at each of them but the 20 only effect produced is to disable the battery supply circuits for the filaments of the repeaters at offices S, Y and Y'.

It is to be noted that all slow operating and releasing relays are indicated as such in 25 the drawings by arrows intersecting the armatures of said relays and pointing in the direction that said armatures are slow to move.

It is believed that the invention will now 30 be fully understood from the following detailed description of the operation.

Operator at office W initiates a call over line circuit A.

- 35 Upon the insertion of plug 1 of a link circuit into jack 10 at office W, a circuit is established extending from grounded battery, through the winding of relay 2 associated with the link circuit, the sleeve contacts of plug 1 and jack 10 and the winding of relay 11 to ground. Relays 2 and 11 energize in this circuit and upon the closure of the contact of relay 11, a circuit is 40 established from grounded battery, through the winding of relay 13, winding of relay 12 and the contact of relay 11 to ground. Relays 12 and 13 are energized in this circuit but relay 12 is slow to operate and consequently a temporary circuit is established 45 from grounded battery, the alternate contact of relay 13, the left-hand winding of relay 14, and the back contact of relay 12 to ground. Relay 14 is energized and locks in a circuit extending from ground at the contact of relay 16, the contact and right-hand winding of relay 14, and the winding of relay 15 to grounded battery. Relay 15 energizes and extends ground from its contact 50 through the left-hand normal contacts of relays 27, 37, 47, 57 and 67 in series and the winding of relay 17 to grounded battery. Upon relay 17 energizing in this circuit, the 55 30 volt battery 71 is included in the physical lines A and C extending between offices W and Y', the latter of which is similar in all 60 65

respects to office Y. This circuit extends from positive pole of battery 71 through the upper winding of polar relay 70, the conductor included in the physical line C, the lower winding of polar relay similar to 70 polar relay 210 at office Y, the normal contact of a relay similar to relay 205 of the latter office, the upper winding of the relay similar to relay 210, the conductor included in the line A extending from office Y' to 75 office W, the lower winding of polar relay 70 and the alternate contact of relay 17 to the negative pole of battery 71. The initiating impulse transmitted by this circuit is 80 repeated at office Y' in a manner which will appear in the course of the description and a circuit is thereby completed which includes the windings of polar relay 100 and the left-hand normal contact of relay 108 at 85 office X, said contact shunting the resistance 172. The strength of the current flowing in this circuit and the direction thereof is such that the upper winding of relay 70 is energized to prevent closure of the contact of said relay, but relay 100 operates to close its contact. An impulse is thereby transmitted to the impulse sending mechanism at the central station X to initiate the operation of this mechanism.

The closure of the contact of relay 100 establishes a circuit extending from ground through a conducting segment of the continuously operating interrupter 104, the contact of relay 100, the normal contact and winding of relay 103, the normal contact of relay 142 to grounded battery 143. Relay 103 energizes and locks from ground through its inner right-hand alternate contact and winding to battery 143. An obvious operating and holding circuit is then established for relay 107. Another interrupter 105 operates in conjunction with the interrupter 104 and these interrupters are so arranged that their conducting segments are alternately grounded. After relay 103 has operated 100 and when the interrupter 105 reaches its next grounded segment, a circuit is established from ground at the interrupter 105 through the outer left-hand alternate contact of relay 103 and the winding of relay 106 to grounded battery. At its left-hand alternate contact, relay 106 establishes an obvious circuit through the left-hand winding of relay 108 which thereupon energizes. The first of a series of impulses is now 110 transmitted from office X simultaneously in both directions. The transmission of these impulses to office W, will first be described.

The first energization of relay 108 establishes a circuit from the positive pole of a 60 volt battery 171 through the upper winding of relay 100, the conductor included in the line circuit A extending between offices X and Y', the windings of a polar relay at the latter office similar to 125 130

the polar relay 200 at office Y, the conductor included in the line C extending between offices Y' and X, and the lower winding of polar relay 100, and the left-hand alternate contact of relay 108 to the negative pole of battery 171. This impulse and succeeding ones are repeated at office Y' as will appear in the description of the apparatus at office Y. The repeated impulse from 5 a source of current such as the 60 volt battery 272 at office Y is transmitted over the conductors included with the lines A and C extending between offices Y' and W, through the windings of polar relay 70 and 10 the resistance 72, the battery 71 being also connected to the lines at this time by the energization of relay 17. In the course of the description where reference is made to the transmission of impulses from office X 15 to office W, it will be understood that, in each instance, these impulses are repeated at office Y'. The strength and direction of flow of current in the above circuit opposing the current from battery 71 is such 20 as to cause relay 70 to close its contact. A circuit is then closed from ground through the contact of relay 70, the right-hand normal contact and winding of relay 27 and the right-hand normal contact of relay 35 25 to grounded battery. Relay 27 energizes and at its left-hand normal contact opens the energizing circuit for relay 17 which releases. Battery 71 is no longer connected to the lines and polar relay 100 at office 30 X therefore releases. Upon the closure of the left-hand alternate contact of relay 27 another circuit is established for relay 17 from battery through the winding of relay 17, the normal left-hand contacts of 35 relays 67, 57, 47 and 37, the left-hand alternate contact of relay 27, the contacts of relays 14 and 16 to ground. The energization of relay 17 at this time again connects the battery 71 to the lines A and C 40 and for a second time effects the energization of polar relay 100 at office X. Therefore, immediately after the termination of the first impulse from office X and when interrupter 104 reaches a grounded segment 45 another impulse is transmitted by the energization of relay 108 over a circuit extending from ground through the interrupter 104, the contact of polar relay 100, the right-hand contact of relay 107 and the right-hand winding of relay 108 to 50 grounded battery. This second impulse is likewise transmitted to office W to energize polar relay 70 in the same manner as previously described. Referring again to the 55 receipt of the first impulse at office W under the control of interrupter 105, relay 27, upon energizing, locks from ground through its middle alternate contact and winding to grounded battery at relay 65 and opens the energizing circuit of relay 17 which 60 then releases. Relay 27 also completes a circuit for relay 28 extending from ground through the right-hand alternate contact of relay 27, the winding of relay 28 and the common battery at relay 65, but relay 28, 70 being slow to operate, does not close its contacts until after the first impulse has terminated. When this occurs, relay 28 establishes a circuit for relay 25 extending from ground at the right-hand contact of 75 relay 28, through the winding of relay 25 to the common battery at relay 65. Relay 25 is also slow to operate and therefore does not close its alternate contact until after the termination of the second impulse. 80 When this impulse is transmitted from the sending mechanism at office X under the control of interrupter 104, polar relay 70 is again operated to close its contact as previously stated, whereupon the ground thereat is extended through the left-hand contact of relay 28, normal contact of relay 25 and the winding of relay 16 to the common battery of relay 65. Relay 16 energizes in 85 this circuit and upon opening its normal contact disables the locking circuit for relay 14 and also causes the deenergization of relay 15. In the remainder of the operation of the series of stepping relays at office W, in this instance, relay 17 does not energize again and therefore no more impulses will be transmitted from office W to office X to cause the operation of relay 108 under the control of interrupter 104. Consequently, all impulses will now be under 90 the sole control of interrupter 105. Upon the termination of the second impulse, relay 70 releases and opens the energizing circuit for relay 16 which then restores and relay 25 then energizes. The next impulse transmitted from office W under the control of interrupter 105 again operates polar relay 70 and the ground is extended from the contact of this relay, through the left-hand contact of relay 28, the alternate contact of relay 25, the right-hand normal contact and winding of relay 37 to the common battery at relay 65. Relay 37 energizes in 100 this circuit and locks, through its winding, and middle alternate contact to ground. It also closes an energizing circuit for relay 38 extending from ground, through the right-hand alternate contact of relay 37, the winding of the relay 38, to the common battery at relay 65. Relay 38 being slow to operate does not close its contacts until after 105 this third impulse has terminated, whereupon a circuit is established for relay 35 extending from ground, through the right-hand contact of relay 38 and the winding of relay 35 to the battery at relay 65. Relay 35 is also slow-to-operate and therefore does not close its alternate contact immediately upon the closure of the circuit 110 therefor. The impulses transmitted from 115 120 125 130

office X being now under the sole control of interrupter 105, it will be obvious that a considerably longer period will elapse between the transmission of impulses than when the two interrupters are conjointly acting to transmit these impulses. Therefore, while the interrupter 105 is passing over a non-grounded segment after the termination of the second impulse and the interrupter 104 is passing over the grounded segment which is ineffective at this time, the relay 35 will have sufficient time to close its alternate contact before the next grounded segment of the interrupter 105 is reached. The impulse transmitted when this occurs again operates the polar relay 70 to close its contact, whereupon the ground is extended therethrough to the left-hand contact of relay 28, the alternate contact of relay 25, the left-hand contact of relay 38, the alternate contact of relay 35, the right-hand normal contact and winding of relay 47 to the common battery at relay 65. By the energization of relay 35, before this impulse is received, it will be apparent that a circuit will not be established through the winding of relay 26 and therefore this relay will fail to operate. Upon the energization of relay 47, the same locks through its winding and middle alternate contact to ground and also establishes an energizing circuit for relay 48, extending from ground, through the right-hand alternate contact of relay 47, and the winding of relay 48, to the common battery at relay 65. Relay 48 being slow to operate, does not close its contacts until after the impulse has terminated whereupon a circuit is established for the slow-to-operate relay 45, extending from ground, through the right-hand contact of relay 48, and the winding of relay 45, to the common battery at relay 65. Relay 45 operates in the same manner as relay 35 and closes its alternate contact before the next impulse is transmitted from office X under the control of interrupter 105 and thus prevents the operation of relay 36. When this next impulse is received at office W, polar relay 70 again operates and the ground at the contact of this relay is then extended over the previously traced circuit as far as the alternate contact of relay 35 and from thence through the left-hand contact of relay 48, the alternate contact of relay 45, the right-hand normal contact and winding of relay 57 to the common battery at relay 65. Relay 57 operates and locks in the same manner as previous similar relays and establishes an obvious energizing circuit for slow-to-operate relay 58 which closes its contacts after the termination of the impulse. This establishes an obvious circuit for slow to operate relay 55 which closes its alternate contact after an

interval in the same manner as previous similar relays and thus prevents the operation of relay 46. Therefore, when the next impulse is received through the winding of polar relay 70 its contact is closed to extend the ground over the previously described circuit as far as the alternate contact of relay 45 and from thence through the left-hand contact of relay 58, the alternate contact of relay 55, the right-hand normal contact and winding of relay 67 to common battery at relay 65. Relay 67 thereupon operates and locks and establishes an obvious circuit for slow-to-operate relay 68 which closes its contacts after the termination of the impulse to establish an obvious energizing circuit for relay 65. At this period of the operation, relay 142 at office X will be operated to disconnect the battery 143 from the locking circuit of relay 103 as will be more specifically described hereinafter and therefore no more impulses will be transmitted from office X. Relay 65, after an interval, energizes and, in opening its right-hand contact, removes the common battery from the circuits of the series of stepping relays at office W, whereupon all of these relays restore to normal. Relays 11, 12 and 13, however, remain in their operated condition due to the engagement of the plug of a link circuit with jack 10. The operation of the series of stepping relays at office X which occurs simultaneously with that of those at office W will now be described. After the energization of relay 103, in response to the initiating impulse transmitted from office W when the plug is inserted into jack 10 and when the first impulse is transmitted from office X by the energization of relays 106 and 108 under the control of interrupter 105, a circuit is established from ground, through the right-hand contact of relay 106, the inner left-hand contact of relay 103, the normal contact and winding of relay 101 and the normal contact of relay 142 to battery 143. Relay 101 energizes and locks in a circuit extending from ground, through its right-hand alternate contact and winding to the battery 143. Relay 101 establishes an energizing circuit for slow-to-operate relay 102 extending from ground, through the left-hand alternate contact of relay 101 and the winding of relay 102 to battery 143. Relay 102, being slow to operate, does not close its contacts until after the termination of the first impulse. As will be recalled, the second impulse transmitted is under the control of the interrupter 104 which closes a circuit through the right-hand winding of relay 108. Relay 106 is therefore not energized and the transmission of this second impulse at office X has no effect upon the stepping relays thereat. During the transmission of the second impulse under the control of interrupter 104

and when polar relay 100 is energized, a circuit is established from ground, through the interrupter 104, the contact of relay 100, the right-hand contact of relay 107, the 5 junction point 113, the right-hand normal contact, left-hand winding and left-hand normal contact of differential filament control relay 109, the left-hand contact of relay 102, this relay having energized after 10 the termination of the first impulse, and the normal contact of relay 142 to the battery 143. Relay 109 energizes in this circuit and locks in a circuit extending from grounded battery, through its left-hand alternate contact, left-hand winding and middle alternate contact to ground. The closure of the right-hand alternate contact of relay 109 connects ground to the battery of the filaments of 15 telephone repeaters RA, RB and RC associated respectively with the lines A, B and C. These repeaters are then rendered effective and remain in this condition as long as a plug is inserted into any one of the jacks at office W. From this point in the 20 operation the impulses are under the sole control of interrupter 105. The next impulse establishes a circuit from ground, through the right-hand contact of relay 106, the inner left-hand alternate contact of relay 103, the right-hand contact of relay 102, the normal contact and winding of relay 111 to battery 143. Relay 111 energizes and locks through its winding and right-hand alternate contact to ground and at its left 25 hand alternate contact establishes an energizing circuit for slow-to-operate relay 112 extending through its winding to battery 143. Relay 112 closes its contact before the next grounded segment of interrupter 105 is 30 reached so that upon the succeeding impulse under the control of this interrupter, the ground from the right-hand contact of relay 106 will be extended through the contacts of relays 102 and 112 and the normal contact 35 and winding of relay 121 to the battery 143. Relay 121 energizes and locks in the same manner as previous similar relays and establishes an obvious circuit for slow-to-operate relay 122 which closes its contact after the 40 termination of the impulse and before the next grounded segment of interrupter 105 is reached. The next succeeding impulse causes the ground from the right-hand contact of relay 106 to be extended through the 45 alternate contacts of relays 102, 112 and 122, the normal contact and winding of relay 131 to battery 143. Relay 131 energizes and locks and establishes an obvious circuit for slow-to-operate relay 132 which closes its 50 contact after the termination of the impulse so that upon the next succeeding impulse the ground from the right-hand contact of relay 106 is extended through the contacts of relays 102, 112, 122 and 132, the normal contact and winding of relay 141 to ground- 55 ed battery. Relay 141 energizes and locks in a circuit extending from grounded battery, through the winding of this relay, the right-hand alternate contact thereof and the left-hand contact of relay 107 to ground. In 60 energizing, relay 141 establishes an obvious circuit for relay 142 which energizes after the termination of the impulse and before the next grounded segment of relay 105 is 65 reached. The energization of relay 142 disconnects the common battery 143 from the circuit of the stepping relay 101, 102, etc. and these relays thereupon restore to normal. Relay 142 is also slow to release and sufficient time will therefore elapse for the 70 release of all of the stepping relays. Relay 142 also disconnects battery 143 from the locking circuit of relay 103 which thereupon deenergizes and opens the holding circuit for relay 107. The mechanism at office X is 75 now in normal condition with the exception of the filament-control relay 109.

The operation at the intermediate telephone repeater office Y which occurs simultaneously with the operation of the 80 apparatus at offices W, Y' and X during the transmission of impulses from the latter office, will now be described. When the interrupter 105 engages a grounded segment after the initiating impulse has 85 been transmitted from office W to office X to operate relay 108 to transmit the first impulse simultaneously in both directions, a circuit is established from the positive pole of battery 171 through the upper winding of polar relay 110, the simplex conductor included with line A extending from office X to office Y, the upper winding of polar relay 200, the normal contact of relay 204, which shunts the resistance 273, the 90 lower winding of polar relay 200, the simplex conductor included with line C extending from office Y to office X, the lower winding of relay 110 and the right-hand alternate contact of relay 108 to the other 95 side of battery 171. The direction and strength of current flowing in this circuit causes the polar relay 200 to operate and close its lower contact whereupon an obvious circuit is established for relay 205 which 100 energizes and connects battery 272 to the windings of polar relays 210 and 370 as will be later more fully described. The current in this circuit operates relay 210 to close its upper contact whereupon a 105 circuit is established from ground through the upper contact of polar relay 210, the normal contact of relay 203, the normal contact and winding of relay 201, and the left-hand normal contact of relay 243 to 110 grounded battery. Relay 201 operates in this circuit and locks up through its winding and left-hand alternate contact to ground. The energization of relay 201 115 establishes a circuit for slow-to-operate 120

relay 202 extending from ground through the right-hand alternate contact of relay 201, the winding of relay 202, and the left-hand contact of relay 243 to grounded battery, 5 but relay 202, being slow to operate, does not close its contacts until after the termination of the first impulse transmitted by the operation of relay 108. When this occurs, a circuit is established from ground through 10 the left-hand contact of relay 202, the winding of relay 203, and the left-hand contact of relay 243 to grounded battery. Relay 203 also being slow to operate will not close its alternate contact until after the termination 15 of the next succeeding impulse. Upon the closure of the upper contact of polar relay 210 in response to the next impulse transmitted from office X which, in this instance, is under the control of interrupter 20 104, a circuit is established from ground through the upper contact of relay 210, the normal contact of relay 203, the right-hand contact of relay 202, the normal contact and left-hand winding of the differential filament 25 control relay 209 to grounded battery. Relay 209 operates in this circuit and locks through its left-hand winding and alternate contact to ground. In closing its right-hand alternate contact, a circuit is closed for the 30 battery supply of the filaments of the telephone repeaters RA-1, RB-1 and RC-1, associated respectively with the lines A, B and C. Relay 209 remains energized in the same manner as differential relay 109 to 35 maintain the battery supply for the telephone repeaters at office Y as long as a plug is inserted in any of the jacks at offices X and Z. After the termination of the second impulse following which the remaining 40 impulses are under the sole control of interrupter 105, relay 203 operates and prepares a circuit which is closed upon the next closure of the upper contact of polar relay 210 extending from ground thereat through the alternate contact of relay 203, 45 the normal contact of relay 213, the normal contact and winding of the relay 211, and the left-hand contact of relay 243 to grounded battery. The impulse which last causes the energization of relay 210 and all 50 of the remaining impulses of the series are now under the sole control of interrupter 105. Relay 211 operates in the circuit just traced and locks in the same manner as relay 201 and also establishes a circuit for relay 212 extending from ground through the right-hand alternate contact of relay 211, the winding of relay 212, and the left-hand contact of relay 243 to grounded battery. 55 Relay 212 is slow to operate and does not close its contact until after the impulse has terminated whereupon an obvious circuit is established for relay 213. The transmission of impulses being now under the sole control of the interrupter 105, the relay 213 operates before the next closure of the upper contact of relay 210 in response to the next impulse transmitted by the operation of relay 108 and upon the closure of 60 said contact, the ground is extended therefrom through the alternate contacts of relays 203 and 213, the normal contact of relay 223, the normal contact and winding of relay 221 and the left-hand contact of relay 243 to grounded battery. Relay 221 70 operates and locks up in the same manner as relay 211 and at its right-hand alternate contact establishes a circuit for relay 222 through its winding to grounded battery at the left-hand contact of relay 243. Relay 222 75 is also slow to operate and does not close its contact until after the impulse has terminated whereupon an obvious circuit is established for relay 223 which, being slow to operate, closes its alternate contact 80 after an interval to extend the ground from the upper contact of relay 210, with the next operation thereof in response to a succeeding impulse, through the alternate contacts of relays 203, 213 and 223, the normal 85 contact of relay 233, the normal contact and winding of relay 231 to grounded battery at the left-hand contact of relay 243. Relay 231 energizes and locks up through its winding and left-hand alternate contact to 90 ground and establishes an obvious circuit for slow-to-operate relay 232 which closes its contact after the termination of the impulse. A circuit is then established for 95 relay 233, which, due to its slow operation, closes its alternate contact after an interval. Upon the next closure of the upper contact of relay 210, the ground thereat, is extended 100 through the alternate contacts of relays 203, 213, 223 and 233, the right-hand contact of 105 relay 243, the normal contact of relay 241 and the left-hand contact of relay 243 to grounded battery. Relay 241 energizes and locks in a circuit from grounded battery, 110 the left-hand contact of relay 243 and the winding and left-hand alternate contact of 115 relay 241 to ground. The energization of relay 241 establishes an obvious circuit for relay 242 which, being slow to operate, does not close its contacts until after the termination of the impulse. By attracting its right-hand contact, relay 242 connects battery through the right-hand winding of relay 209, but this relay is unaffected at this time, since relay 242 does not energize until after the last impulse has been transmitted from office X, the further transmission of impulses being prevented by the release of relay 103 as previously described. 120 The energization of relay 242 establishes an obvious circuit for relay 243 which, being slow to operate, opens its normal contacts before interrupter 105 reaches another grounded segment, and disconnects 125 the common battery supply from its left- 130

hand contact whereupon the locking and holding circuits of the chain of relays including relays 201, 202, 203, etc., are opened and said relays release before relay 243, 5 which is also slow to release, is deenergized. The apparatus at office Y is now in normal position with the exception of relay 209 which remains energized the same as relay 109.

10 The operation of the chain of relays at office Z corresponding to those relays just described at office Y and which are operated by the transmission of impulses from office X, will now be described. Upon each closure 15 of the lower contact of polar relay 200, the relay 205 is energized as briefly referred to hereinbefore to include the 69 battery 272 in the lines extending from office Y to office Z. When so included, a circuit is established 20 from the positive pole of battery 272 through the alternate contact of relay 205, the lower winding of polar relay 210, the conductor included in the line C extending from office Y to office Z, the upper winding of polar 25 relay 370, the normal contact of relay 317 which shunts resistance 372, the lower winding of relay 370, the conductor included in the line A extending from office Z to office Y, and the upper winding of polar relay 210 30 to the negative pole of battery 272. The strength and direction of flow of current in this circuit is such as to cause the polar relays 210 and 370 to operate and close their upper contacts. The effects of the closure 35 of the upper contact of relay 210 has already been described. The closure of the contact of polar relay 370 operates to extend ground therefrom through the left-hand normal contact and winding of relay 327 to the common battery at the left-hand contact of relay 365. Relay 327 operates in this circuit and locks through its winding and middle alternate contact to ground. By closing its left-hand alternate contact, a circuit is established 40 for relay 328 extending from grounded battery through the left-hand contact of relay 365, the winding of relay 328 and the left-hand alternate contact of relay 327 to ground. However, relay 328 is slow 45 to operate and does not close its contacts until after the first impulse has terminated. When this occurs, a circuit is established for slow-to-operate relay 325 extending from the common battery at relay 365 through 50 the winding of relay 325 and the left-hand contact of relay 328 to ground. Relay 325 does not close its alternate contact until after the termination of the next succeeding impulse. At the termination of the first impulse, relay 205 releases to disconnect the battery 272 from the polar relay 370 which thereupon releases to open its contact. When said next succeeding or second impulse is transmitted which occurs immediately after 55 the termination of the first impulse and un-

der the control of interrupter 104, relay 370 is again operated and relay 328 being now energized, the ground at the contact of relay 370 is extended through the right-hand contact of relay 328, the normal contact of relay 325, the winding of relay 316 to the common battery at relay 365. Relay 316 operates in this circuit but has no effect, since relay 314 is not, at this time, energized. At the termination of the second impulse, 70 relay 325 closes its alternate contact and thus permanently opens the circuit for relay 316. All succeeding impulses are now under the sole control of interrupter 105. The next impulse transmitted again operates relay 370 75 and the ground is then extended through the right-hand contact of relay 328, the alternate contact of relay 325, the left-hand normal contact and winding of relay 337 to the common battery at relay 365. Relay 80 337 operates and locks up in the same manner as relay 327 and at its left-hand alternate contact closes a circuit for relay 338 which, being slow to operate, does not close its contacts until after the termination of 85 this impulse at which time relay 338 establishes an obvious circuit for slow-to-operate relay 335 which closes its alternate contact before interrupter 105 reaches the next 90 grounded segment to transmit another impulse. Upon the transmission of this impulse, the ground, is extended from relay 370 through the right-hand contact of relay 328, the alternate contact of relay 325, the right-hand contact of relay 338, the alternate contact of relay 335, the left-hand normal contact and winding of relay 347 to the common battery at relay 365. By passing through the alternate contact of relay 335 the current is prevented from energizing 95 relay 326. Relay 347 energizes and locks up through its winding and middle alternate contact to ground. The closure of the left-hand alternate contact of relay 347 establishes a circuit for slow-to-operate relay 100 348 to the common battery at relay 365. Relay 348 operates to close its contacts after the termination of the impulse and in so doing, establishes a circuit for relay 345 extending from the common battery at relay 105 365 through the winding of relay 345 to ground at the left-hand contact of relay 348. Relay 345 is also slow to operate and does not close its alternate contact until just previous to the transmission of the next 110 succeeding impulse. At the beginning of the latter impulse, ground at relay 370 is extended as previously described, to the alternate contact of relay 335 and from thence through the right-hand contact of relay 348, the alternate contact of relay 345, the left-hand normal contact and winding of relay 357 which is connected to the common battery at relay 365. 115

120 The opening of the normal contact of re- 125 130

lay 345 prevents operation of relay 336. Relay 357 operates and locks up in the same manner as described in connection with the other similar relays. A circuit is then established for slow-to-operate relay 358 extending from ground at the left-hand alternate contact of relay 357 to battery at relay 365 and after the termination of the impulse, relay 358 closes its contacts. An obvious circuit is then established for slow-to-operate relay 355, but this relay is not energized until after an interval and before the next succeeding impulse is transmitted, so that relay 346 will also be prevented from operating on the next impulse. The next operation of the relay 370 in response to the following impulse extends the ground from the contact thereof over the previously described circuit as far as the alternate contact of relay 345 and from thence through the right-hand contact of relay 358, the alternate contact of relay 355, the left-hand normal contact and winding of relay 367 to common battery at relay 365. Relay 367 energizes and locks up through its winding and middle alternate contact and at its left-hand alternate contact establishes a circuit for slow-to-operate relay 368 to the common battery at relay 365. Relay 368 closes its contacts after the termination of this impulse and establishes an obvious circuit for slow-to-operate relay 365. This relay closes its contacts during the passage of the interrupter 105 over a non-grounded segment so as to open the circuit for relay 356 which extends through the right-hand contact of relay 365, thus preventing the operation of the relay 356 at this time. By opening its left-hand contact, relay 365 removes the common battery therefrom and causes the release of the chain of relays including relays 325, 327, 328, etc. The foregoing operations of the series or chains of relays at the various offices are the result of the insertion of the plug 1 of a link circuit into jack 10 at office W, and after all of these relays have been restored to normal, a condition exists wherein the filament control relays 109 and 209 are energized and locked so as to render effective the various telephone repeaters at offices X, Y and Y'. Also the relays 11, 12 and 13 at office W remain energized due to the engagement of the plug in jack 10.

55 *Operator at office W rings over line A.*

With the impulse mechanism at office X and the series of relays at the various offices in normal condition, the operator at office W, by depressing the ringing key 3 of the link circuit connected to line A, establishes a circuit for the ringing-response relay 24 extending from the source of ringing current through the lower alternate contact of ringing key 3, the ring contacts of the plug 1

and jack 10, the left-hand normal contact of relay 19, the right-hand winding of relay 24, the right-hand normal contact of relay 19, the tip contacts of jack 10 and plug 1 and the upper alternate contact of ringing key 3 to ground. Relay 24 locks in an energizing circuit for relay 15 which extends from grounded battery through the winding of relay 15, the left-hand winding and alternate contact of relay 24, and the normal contact of relay 26 to ground. The energization of relay 15 closes a circuit for relay 17 extending from ground through the contact of relay 15, the left-hand normal contacts of relays 27, 37, 47, 57 and 67 in series and the winding of relay 17 to grounded battery. Relay 17 energizes and connects battery 71 through the windings of relay 70 to the conductors included in the physical lines extending between office W and office Y' which, as previously stated, is similar in all respects to the intermediate telephone repeater station Y.

The impulse produced by the connection of battery 71 across the line is repeated at office Y', as will later appear in connection with the transmission of an impulse from office Z to office X, so as to cause the operation of the polar relay 100 and thereby close a circuit from ground through a conducting segment of the interrupter 104, the contact of relay 100, the normal contact and winding of relay 103 and the normal contact of relay 142 to battery 143. Relay 103 energizes and locks as previously described and in so doing, establishes a circuit for relay 107. When the interrupter 104 passes from the grounded segment, the interrupter 105 reaches its next grounded segment and an obvious circuit is thereupon established for relay 106 as before. In closing its left-hand contact, relay 106 establishes an energizing circuit for relay 108 through the left-hand winding thereof which thereupon energizes to connect the 60V battery 171 through the windings of relay 100 to the polar relay at office Y' which corresponds to the polar relay 200 at office Y. The impulse is here repeated by the energization of a relay at office Y similar to relay 205 which thereupon connects the 60V battery corresponding to battery 272 to the physical lines extending between office Y' and office W. This current, passing through the windings of relay 70 and the resistance 72 and in opposing the current from battery 71, is of such strength as to cause the operation of relay 70 so as to close its contact. A circuit is then established for relay 27 extending from ground through the contact of relay 70, the right-hand normal contact and winding of relay 27 to the common battery at relay 65. Relay 27 energizes and at its left-hand normal contact opens the energizing circuit for relay 17 which thereupon releases and discon-

nects the battery 71 from the lines extending between office W and Y', thus causing the release of the polar relay 100 at office X. The energization of relay 27 also closes a circuit for slow-to-operate relay 28 extending from ground through the right-hand alternate contact of relay 27, winding of relay 28 to the common battery at relay 65. Relay 28 however, does not close its contacts until after the termination of the impulse which is transmitted when the interrupter 105 engages a non-grounded segment. When this occurs, relay 28 energizes and at its right-hand contact establishes a circuit for slow-to-operate relay 25 to the common battery at relay 65. Relay 25 operates during a period when the interrupter 105 is passing over a non-grounded segment and the interrupter 104 over a grounded segment. Since the energizing circuit for relay 17 has now been permanently opened upon the energization of relay 27, it will be apparent that battery 71 will not be connected to the physical lines to transmit another impulse through office Y' to office X to operate polar relay 100 and therefore, while the interrupter 104 is on a grounded segment, no circuit will be closed through the right-hand winding of relay 108 as previously described. Therefore, this relay will not operate to transmit another impulse immediately after the first one has been transmitted. It will, therefore, be apparent that the next impulse from office X is, at this time, under the control of the interrupter 105. Relay 25 operates before the next grounded segment of interrupter 105 is reached so that when this occurs and relay 108 is energized by the operation of relay 106, another impulse will be transmitted in the same manner as previously described to energize the polar relay 70. The ground at the contact of this relay is now extended through the left-hand contact of relay 28, the alternate contact of relay 25, the right-hand normal contact and winding of relay 37 to common battery at relay 65. Relay 37 energizes and immediately establishes a circuit for relay 17 extending from ground at the normal contact of relay 26 through the alternate contact of relay 24, the left-hand alternate contact of relay 37, the left-hand normal contacts of relays 47, 57 and 67 in series and the winding of relay 17 to grounded battery. On this second impulse, therefore, the relay 17 operates to again connect battery 71 to the lines to transmit an impulse to office X which will again operate polar relay 100 when the interrupter 105 passes onto a non-grounded segment. The interrupter 104 now controls the transmission of another or third impulse from office X by the closure of the circuit from ground through the conducting segment thereof, the contact of relay 100, the right-hand contact of relay 107 and the right-hand winding of relay 108 to grounded battery. Relay 108 energizes and connects battery 171 to the lines extending between office X and office Y' where this impulse is repeated by the relay similar to relay 205 at office Y, and the strength of the current in this circuit is such as to again oppose the battery 71 and cause relay 70 to close its contact. It will, therefore, be obvious that immediately upon the termination of the impulse controlled by the interrupter 105, another impulse is transmitted from office X by the grounding of a conducting segment of the interrupter 104. In the meanwhile, relay 37 having energized, the same closes a circuit for relay 38 which extends from ground through the right-hand alternate contact of relay 37, the winding of relay 38 to grounded battery at relay 65. Relay 38, being slow to operate, does not close its contact until after the termination of the impulse controlled by the interrupter 105. Relay 38, in closing its right-hand contact, establishes a circuit for slow-to-operate relay 35 to common battery at relay 65, but relay 35, does not close its contact until after the termination of the impulse transmitted by the interrupter 104. Therefore, when relay 70 is operated by this latter impulse, the ground is extended through its contact, the left-hand contact of relay 28, the alternate contact of relay 25, the left-hand contact of relay 38, the normal contact of relay 35 and the winding of relay 26 to battery at relay 65. Relay 26 energizes and in so doing opens the previously described locking circuit for relay 24, and energizing circuit for relay 15 both of which relays release, the operator having previously released the ringing key 3. The release of relay 15 removes the holding ground for relay 17 which thereupon releases and disconnects the battery 71 from the lines A and C extending between offices W, Y' and X. After the transmission of the impulse by interrupter 104 and before interrupter 105 reaches the next grounded segment, relay 35 energizes over the circuit previously described for it and thereby opens the energizing circuit for relay 26 which thereupon releases. Relays 15 and 17 are now released and remain in their normal conditions throughout the remainder of the operations. The last impulse transmitted by the interrupter 104 is the signaling impulse which determines at office Z, by the operation of relay 319 thereat, the particular line over which the call has been initiated at office W, as will appear in the description of the operation of the transmission of this impulse from office X to office Y and from thence to office Z. From this point of operation, the transmission of impulses from office X is under the sole control of interrupter 105, since relay 17 does not again operate to

transmit an impulse from office W to office X.

Upon the next operation of relay 108 under the control of interrupter 105 and relay 106, relay 70 is again operated as before and the ground on its contact is extended over the previously described path to the alternate contact of relay 35 and from thence through the left-hand normal contact and winding of relay 47 to the common battery at relay 65. Relay 47 energizes and locks up through its winding and middle alternate contact to ground and at the same time establishes a circuit from ground through the right-hand alternate contact and winding of relay 48 to the common battery at relay 65. Relay 48, being slow to operate, does not close its contacts until after the termination of the impulse transmitted from office X, whereupon a circuit is established from ground through the right-hand contact of relay 48 and the winding of relay 45 to common battery at relay 65. Relay 45, being slow to operate, closes its alternate contact before the next grounded segment of interrupter 105 is reached so that upon the next impulse transmitted by the energization of relay 108, relay 45 will have already closed its alternate contact. Therefore, when relay 70 again energizes, the ground extended over the previously described circuit and through the left-hand contact of relay 48 will not be transmitted through the winding of relay 36 but will be extended through the alternate contact of relay 45 to the winding of relay 57 and from thence to the common battery at relay 65. Relay 57 operates and locks to establish an obvious circuit for the slow-to-operate relay 58 which closes its contacts after the termination of the impulse. In so doing, an obvious circuit is established for relay 55, and this relay, being slow to operate, closes its alternate contact before the next grounded segment of the interrupter 105 is reached. Therefore, when the next impulse is transmitted and relay 70 operated, the ground through its contact is extended over the previously traced circuit as far as the alternate contact of relay 45 and from thence through the left-hand contact of relay 58, the alternate contact of relay 55, which prevents the operation of relay 46, the right-hand normal contact and winding of relay 67 to the common battery at relay 65. Relay 67 operates in this circuit and locks up in the same manner as previous similar relays and establishes an obvious circuit for relay 68 which, being slow to operate, does not close its contacts until after the termination of the impulse. When this occurs, the ground at the right-hand contact of relay 68 is extended through the winding of relay 65 to the common battery, thus establishing a circuit for this relay.

Relay 65 also being slow to operate opens its contacts after an interval and before interrupter 105 again reaches a grounded segment. By opening its right-hand contact, relay 65 disconnects the common battery 70 from the circuits previously described for the chain of relays including relays 25, 27, 28, etc., and these relays thereupon restore to normal.

After the first impulse is transmitted to office X by the operation of the ringing key at office W and when relay 106 is energized by the grounding of the first conducting segment of interrupter 105 following the operation and locking of relay 103, a circuit is established from ground through the right-hand contact of relay 106, the inner left-hand alternate contact of relay 103, the normal contact and winding of relay 101, the normal contact of relay 142 to battery 143. 80 Relay 101 energizes and initiates the operation of the series of relays 102, 111, 112, etc., in the same manner as previously described with the exception that, upon the energization of relay 102, a circuit is no 90 longer established through the left-hand winding of relay 109, since this relay is now locked. When relay 142 is energized in this operation, the common battery 143 is disconnected from the relays of the series and 95 the same then restore to normal.

The transmission of impulses from office X to office Y which occurs simultaneously with the transmission thereof from office X to office W will now be described and it will 100 be understood that this same operation takes effect at office Y. Upon the first energization of relay 108, a circuit is established from the positive pole of battery 171 through the upper winding of relay 110, 105 the conductor included in the line circuit A extending between office X and office Y, the upper winding of relay 200, the normal contact of relay 204 which shunts the resistance 273, the lower winding of relay 200, the conductor included in the line circuit C extending between office Y and office X, the lower winding of relay 110 and the right-hand alternate contact of relay 108 to the negative pole of battery 171. Polar relay 110 110 operates to close its lower contact to establish the previously described circuit for relay 205 which, in connecting battery 272 to the windings of polar relay 210 to cause this relay to close its upper contact as before described, initiates the operation of the series of relays 202, 203, 311, 312, 313, etc., with the same result as previously described with the exception that the energizing circuit for the differential filament control relay 209 is not closed at this time, since the same is now locked. The energization of relay 243 in the operation of this series of relays disconnects the common battery from the 120 relays which thereupon restore to normal. 130

The effect of the transmission of impulses from office X to office Z will now be described. Upon the operation of the polar relay 200 to close the energizing circuit for relay 205 as previously described, the battery 272 is connected through the windings of the polar relay 210 to the conductors included in the physical lines A and C extending between office Y and office Z and from thence through the windings of the polar relay 370 and the normal contact of relay 317. The current flowing through this circuit is such as to operate polar relay 370 to close its contact when the initial impulse is transmitted. A circuit is then established, from ground through the contact of relay 370, the left-hand normal contact and winding of relay 327 and the left-hand normal contact of relay 365 to grounded battery. Relay 327 energizes and, as before, establishes a circuit for relay 328 which, however, does not close its contacts until after the termination of the impulse, whereupon a circuit is established for slow-to-operate relay 325 extending from ground at the left-hand contact of relay 328 through the winding of relay 325 to the common battery at relay 365. The transmission of impulses from office X being, at this time, under the sole control of interrupter 105 as described in connection with the series of operations at office W, it will be obvious that relay 325 will operate before the next impulse is transmitted to office Z and therefore, this next impulse will not close a circuit through the normal contact of relay 325 for relay 316 but the ground at the contact of relay 370, upon the operation of such relay in response to this second impulse will be extended through the alternate contact of relay 325, the left-hand normal contact and winding of relay 337 to battery at relay 365. It is at this period of the operation at office W that relay 37 is operated to close the circuit for relay 15 which extended through the left-hand winding and alternate contact of relay 24 to ground at the relay 26, with the result that relay 17 was energized to transmit an impulse to office X to operate the polar relay 100 so that the interrupter 104 would control the transmission of the next impulse by the energization of relay 108 through its right-hand winding. When the circuit is established through the winding of relay 337, this relay energizes and locks in the same manner as before and again establishes the energizing circuit for relay 338 which does not close its contacts, however, until after the termination of the impulse. When this occurs, relay 338 establishes an energizing circuit for relay 335 but this relay does not close its alternate contact until after the next impulse under the control of interrupter 104 is terminated. The succeeding impulse controlled by the interrupter 104 is transmitted to office Z to energize polar relay 370 and relay 338 now being energized, the ground at the contact of relay 370 is extended through the right-hand contact of relay 328, the alternate contact of relay 325, the right-hand contact of relay 338, the normal contact of relay 335 and the winding of relay 326 to battery at relay 365. Relay 326 energizes and establishes a circuit for relay 319 extending from grounded battery through the left-hand contact of relay 365 the winding of relay 319, and the alternate contact of relay 326 to ground. Relay 319 energizes and thereupon establishes a circuit extending from the source of ringing current 373 through the alternate contacts of relay 319 and the winding of the ring-down drop or signal controlling relay 349. The operator at office Z observing the operated condition of this signal device, thereupon inserts the plug 1 of a link circuit into jack 310 which disconnects the drop 349 from the source of signaling current 373 and connects the terminals of the line A with the tip and ring conductors of the link circuit. As soon as relay 319 releases, which occurs at the termination of the impulse which energized relay 326, the operator at office Z may actuate the listening key 4 of the link circuit and thus connect her telephone set (not shown) to the line and thereby establish connection with the operator at office W. Immediately upon the release of relay 326, the slow-to-operate relay 325 is energized in order to extend the ground at polar relay 370 upon the reception of the next succeeding impulse at office Z. From this point in the operation, the transmission of impulses from office X is again under the sole control of the interrupter 105, since the relay 17 is now permanently restored to normal as described in connection with the operation at office W. The next impulse received at office Z operates the relay 347 and relays 348, 345, 357, 358, 355, 367, 368 and 365 operate in the same manner as previously described when the succeeding impulses are transmitted to office Z. The operation of relay 365 again removes the common battery from the circuits of relays which have been operated at office Z and these relays are again restored to normal.

Upon the insertion of the plug 1 into jack 310, a circuit is established from grounded battery through the winding of relay 2 of the link circuit, the sleeve contacts of plug 1 and jack 310 and the winding of relay 311 to ground. Relay 311 energizes and completes a circuit for relays 312 and 313 extending from grounded battery through the windings of relays 313 and 312 and the contact of relay 311 to ground. Relay 312, being slow to operate, does not immediately close its alternate contact and a circuit is

therefore, momentarily established for relay 314 extending from grounded battery through the alternate contact of relay 313, the right-hand winding of relay 314 and the 5 normal contact of relay 312 to ground. Relay 314 energizes and locks up in a circuit extending from ground at the contact of relay 316, the contact and left-hand winding of relay 314, and the winding of relay 315 10 to grounded battery. Relay 315 energizes in this circuit and prepares a circuit for relay 317 which is closed after the energization of relay 365 and the consequent release of the series of relays as previously 15 described. This circuit is then extended from ground at the contact of relay 315, the right-hand normal contacts of relays 327, 337, 347, 357 and 367 in series and the winding of relay 317 to grounded battery. Relay 20 317 energizes and establishes a circuit from the positive pole of battery 371, through the upper winding of polar relay 370, the conductors included in the line circuit C extending between office Z and office Y, the 25 lower winding of polar relay 210, the normal contact of relay 205 which shunts the resistance 274, the upper winding of relay 210, the conductors included in the line circuit A extending between office Y and office 30 Z, the lower winding of polar relay 370 and the alternate contact of relay 317 to the negative pole of battery 371. The strength of current and the direction of flow thereof in this circuit operates the polar relay 210 35 to close its lower contact and cause the energization of relay 204 over an obvious circuit so that the impulse transmitted from office Z will be repeated at office Y over a circuit extending from the positive pole of battery 40 271 through the upper winding of polar relay 200, the conductors included in the physical line A extending between office Y and office X, the upper winding of polar relay 110, the right-hand normal contact 45 of relay 108 which shunts the resistance 173, the lower winding of polar relay 110, the conductors included in the physical line C extending between office X and office Y, the lower winding of polar relay 200 and the 50 alternate contact of relay 204 to the negative pole of battery 271. This is the circuit previously referred to which produces the repetition of impulses at office Y' from office X. The strength and direction of flow of current 55 in this circuit is such as to operate relay 110 to close its contact whereupon a circuit is established for relay 103 extending from ground through a conducting segment of the interrupter 104, the contact of relay 110, the normal contact and winding of 60 relay 103, the normal contact of relay 142 to battery 143. Relay 103 energizes and locks as before and initiates the operation of the impulse sending mechanism at office X which operates to transmit impulses there-

from simultaneously in both directions to operate the series of stepping relays at offices W, Y', Y and Z in the same manner as described in connection with the initiation of a call at office X by the insertion of a 70 plug into jack 10. This operation, however, has no effect upon the system. At the termination of the operation, the various relays at the different offices are again restored to normal, as previously described, 75

Operator at office W initiates a call to office X over the phantom line B.

The insertion of the plug 1 of another link circuit at office W into jack 20 has no immediate effect upon the system since the relays 11, 12 and 13 are already operated by the engagement of the plug in jack 10 and relay 14 will, therefore, not be energized as described in connection with the initiation of a 80 call over line A. However, upon the operator at office W actuating ringing key 3 of the link circuit connected to jack 20, relay 34 will operate over a circuit extending from a source of signaling current through the lower alternate contact of key 3, the ring contacts of plug 1 and jack 20, the left-hand normal contact of relay 29, the right-hand winding of relay 34, the right-hand normal contact of relay 29, the tip contacts of jack 20 and plug 1 and the upper alternate contact of ringing key 3 to ground. Relay 34 is responsive to this signaling current and upon energizing, establishes a locking circuit for itself and an energizing circuit for 85 relay 15 extending from grounded battery through the winding of relay 15, the left-hand winding and alternate contact of relay 34, and the normal contact of relay 36 to ground. Relay 15 energizes and establishes a previously described energizing circuit for relay 17 through the left-hand normal contact of relays 27, 37, 47, 57, and 67 in series. Relay 17 energizes and connects battery 71 through the windings of 90 polar relay 70 to the conductors included in the physical lines A and C extending between office W and office Y' and through the windings of a polar relay thereat corresponding to the relay 210 at office Y. The 95 current flowing in this circuit causes the latter relay at office Y to operate in the same manner as previously described in connection with the transmission of an impulse from office Z and the impulse from office W 100 is, therefore, repeated at office X to operate the polar relay 100 as before. Relay 103 is again operated through the interrupter 104 to initiate the transmission of impulses from office X in both directions. These impulses 105 are transmitted to office Y and Y' and the mechanisms thereat together with that at office X are operated and restored to normal in the same manner as described in connection with the transmission of impulses when 110

the operator at office W rings over line A to energize relay 24. The first impulse received at office W after the operation of the impulse mechanism at the central office has 5 started and which impulse is under the control of interrupter 105 operates relay 27 with the same result as previously described, a circuit being established for relay 28 which closes its contacts upon the termination of 10 the first impulse, and establishes a circuit for relay 25. When relay 27 energizes, the energizing circuit for relay 17 is opened and this relay does not again energize until after the several impulses have been transmitted. 15 Therefore, no impulses will be sent from office W to office Z by the energization of relay 108 under the control of interrupter 104 and the transmission of impulses will, for a time, be under the sole control 20 of interrupter 105. After the establishment of the circuit for relay 25 upon the termination of the first impulse from office X, the interrupter 104 will be passing over a grounded segment with no effect upon the 25 system, and the interrupter 105 will be passing over a non-grounded segment. During this interval and before interrupter 105 again reaches a grounded segment, relay 25 energizes so that upon the transmission of 30 the second impulse from office X, the ground at relay 70 will not be closed through the winding of relay 16 but will be transferred through the alternate contact of relay 25 to energize relay 37. This relay then causes 35 the closure of the circuit for relay 38 which, in closing its contacts after the termination of the second impulse, establishes a circuit for relay 35 and this relay, like relay 25, operates during the interval between the 40 ending of the second impulse and the beginning of the third, so that relay 26 will be prevented from operating. On the third impulse, the ground at relay 70 is extended through the winding of relay 47 to energize 45 the same whereupon a circuit is again established for relay 17 extending from grounded battery through the winding of this relay, the left-hand normal contacts of relays 67 and 57, the left-hand alternate contact of relay 47, the alternate contact of 50 relay 34, and the normal contact of relay 36 to ground. Relay 17 again energizes to cause the transmission of an impulse to office X as before which results in the operation of polar relay 100 and the energization of relay 108 through its right-hand winding under the control of interrupter 104. Therefore, immediately upon the termination of the third impulse, another or 55 fourth impulse is transmitted from office X to office W. In the meanwhile, relay 48 is energized and the circuit for relay 45 is established but this relay does not energize until after the termination of the last-named 60 impulse from office X which is under the

control of the interrupter 104. Therefore, the ground at the polar relay 70 is extended through the left-hand contact of relay 48, the normal contact of relay 45, the winding of relay 36 to the common battery at relay 65. Relay 36 energizes and removes the locking ground for relays 34 and 15 which thereupon release. 70

The deenergization of relay 15 permanently opens the circuit for relay 17 which thereupon releases. At the termination of the impulse, relay 45 energizes and opens the circuit for relay 36 which thereupon restores. For the remainder of the operation, the impulses transmitted from office X 80 are again under the sole control of the interrupter 105 so that upon the receipt of the succeeding impulses at office W, the relays 57, 58, 55, 67, 68 and 65 will operate in the same manner as described in connection with relays 27, 28 and 25. Relays 46 and 56 will, therefore, remain in their normal conditions and, upon the energization of relay 65, the series of stepping relays at office W 85 are restored to normal. 90

Simultaneously with the operation of the various relays at office W in response to the impulses transmitted from office X, the mechanism at office Z is operated by the repetition of these impulses at office Y. The first impulse operates relays 327 and 328 in the same manner as relays 27 and 28 and after the termination of the first impulse and before the receipt of the second impulse, relay 325 operates so as to prevent the operation of relay 316. The second impulse transmitted operates relays 337 and 338 and before the third impulse is transmitted, relay 335 operates to prevent the energization of relay 326. On the third impulse, relay 347 energizes and establishes a circuit for relay 348 which closes its contacts at the termination of this impulse to establish the circuit for relay 345. As before described, this third impulse is under the control of interrupter 105 and the succeeding or fourth impulse is under the control of interrupter 104 due to the energization of relay 17 when relay 47 was operated. The fourth impulse being received at office Z immediately after the termination of the preceding impulse causes the operation of relay 336 over a circuit extending from the common battery at relay 365, the winding of relay 336, the normal contact of relay 345, the right-hand contact of relay 348, the alternate contact of relay 335, the right-hand contact of relay 338, the alternate contact of relay 325, the right-hand contact of relay 328 and the contact of polar relay 370 to ground. Relay 336 operates and closes a circuit for relay 329 extending from ground through the contact of relay 338 and the winding of relay 329 to grounded battery at relay 365. The source of signal- 100 105 110 115 120 125 130

ing current 373 is then extended through the alternate contacts of relay 329 and the winding of drop 359 which, upon energizing, displays the signal associated with phantom line B at office Z to indicate to the operator thereat that a call has been initiated on this line. At the termination of the impulse which energizes relay 336, relay 345 energizes and the impulses from office X now 5 being again under the sole control of the interrupter 105, the relays 357, 358, 355, 367, 368 and 365 are operated in the same manner as relays 327, 328 and 325. The energization of relay 365 removes the common battery 10 from the series of stepping relays at office Z and these relays then restore to normal.

The operator at office Z observing the operated condition of the signal associated 20 with the line B, inserts plug 1 of another link circuit into jack 320 to open the circuit for drop 359 and by operating her listening key 4 a channel of communication is established between the operators at office 25 W and office Z. The insertion of the plug into jack 320 does not have the same effect as described in connection with the insertion of the plug into jack 310, since relays 311, 312 and 313 are now operated and an impulse 30 will not be transmitted from office Z to office X.

Operator at office W initiates a call to office Z over line C.

35 The insertion of a plug of the link circuit into jack 30 has no immediate effect upon the system at office W but upon the operator thereat depressing ringing key 3, a circuit is established from source of signaling current through the lower alternate contact of key 3, ring contacts of the plug 1 and jack 30, the left-hand normal contact of relay 39, the right-hand winding of relay 44, the right-hand normal contact of relay 39, the 40 tip contacts of jack 30 and plug 1 and the upper alternate contact of ringing key 3 to ground. Relay 44 is responsive to the signaling current in this circuit and upon energizing locks in a circuit extending from ground at battery through the winding of relay 15, the left-hand winding and alternate contact of relay 44 and the normal contact of relay 46 to ground. Relay 15 energizes 45 in this circuit and as before, establishes an energizing circuit for relay 17 which operates again to transmit an initiating impulse to office X to energize relay 103. The impulse mechanism at office X again starts to operate to transmit impulses simultaneously 50 in both directions. These impulses control the series of stepping relays at offices X, Y and Y' as before. The impulses transmitted from office X in this instance are under the sole control of the interrupter 105 until 55 the impulse which operates relay 57 at office

W is received. Upon the operation of this relay, a circuit is closed for relay 17 extending from grounded battery through the winding of this relay, the left-hand alternate contact of relay 57, the alternate contact of 70 relay 44 and the normal contact of relay 46 to ground. Relay 17 operates to again transmit an impulse to office X which operates the polar relay 100 so that relay 108 will energize through its right-hand winding under the control of the interrupter 104. This causes another impulse to be transmitted immediately after the termination of the impulse which operates relay 57 and, since relay 58 is, in the meanwhile, energized, the ground from the contact of relay 70 will be extended through the left-hand contact of relay 58, the normal contact of relay 55, which relay is not at this time energized, and the winding of relay 46 to the 80 common battery at relay 65. Relay 46, in energizing, opens the locking circuit for relays 44 and 15 which now permanently restore and upon the termination of the impulses, the circuit for relay 46 is opened and 90 relay 55 then closes its alternate contact. The succeeding impulses from office X are now again under the sole control of interrupter 105 and relays 67, 68 and 65 are operated in the same manner as described 95 in connection with relays 27, 28 and 25. The energization of relay 65 removes the common battery supply from the series of stepping relays at office W and these relays thereupon restore.

The series of impulses received at office Z under the sole control of the interrupter 105 operate the groups of stepping relays at office Z in sequence in the same manner as described in connection with relays at 100 office W until the impulse under the control of the interrupter 104 is transmitted. At this time, relays 357 and 358 are operated and a circuit is established for relay 355. Upon the receipt of the last named impulse, 105 the ground at the contact of relay 370 is extended through the right-hand contact of relay 358, the normal contact of relay 355 and the winding of relay 346 to the common battery at relay 365. Relay 346 energizes 110 and establishes a circuit from said common battery through the winding of relay 339 and the alternate contact of relay 346 to ground. Relay 339 energizes and through its alternate contact, connects the source of signaling current 373 to the winding of drop 369 which controls the signal associated with the line C at office Z. After the termination of the impulse which energizes relay 346, relay 355 closes its alternate contact so that the 115 succeeding impulses which are again under the sole control of interrupter 105 operate the relays 367, 368 and 365 in the same manner that the relays of the first group of the series are operated. The operation of relay 120 125 130

365 removes the common battery supply from the series of stepping relays at office Z and these relays thereupon restore to normal.

5 The operator at office Z observing the actuated condition of the signal associated with line C inserts the plug 1 of another link circuit into jack 330 which opens the circuit for drop 369 and upon the operator actuating 10 the listening key 4, she may then converse with the operator at office W.

Operator at office Z transmits a disconnect signal to operator at office W.

15 Upon the completion of the conversation over the line A, the operator at office Z actuates the ringing key 3 of the link circuit engaging jack 310 and thereby closes a circuit 20 extending from the source of ringing current through the lower alternate contact of ringing key 3, the ring contacts of plug 1 and jack 310, the right-hand normal contact of relay 319, the left-hand winding of relay 25 324, the left-hand normal contact of relay 319, the tip contacts of jack 310 and plug 1 and the upper alternate contact of ringing key 3 to ground. Relay 324 is responsive to 30 this signaling current and in closing its alternate contact, establishes a locking circuit for itself extending from grounded battery through the winding of relay 315, the right-hand winding and alternate contact of relay 324, and the normal contact of relay 326 to ground. Relay 315 energizes and the stepping 35 relays at office Z being now in normal condition, a circuit is established for relay 317 extending from ground, at the contact of relay 315, through the right-hand normal contacts of relays 327, 337, 347, 357 and 367 in series and the winding of relay 317 to grounded 40 battery. Relay 317 in energizing connects the battery 371 through the windings of polar relay 370 to the conductors included 45 in the physical lines A and C extending between office Z and office Y and the windings of the polar relay 210. The latter relay responds to the current flowing through this circuit to energize relay 204 as before which, 50 through battery 271, repeats the impulse transmitted from office Z and thereby causes the energization of polar relay 110, to cause the operation of relay 103 as in the previous instances. The impulse sending mechanism at office X now operates in the same manner as previously described to transmit impulses simultaneously therefrom in both directions. The first impulse transmitted under the control of interrupter 105 causes the operation of polar relay 200 at office Y in the manner previously described and through the agency of the relay 205, this impulse is repeated by the battery 272 to cause the energization of the polar relay 370 at office Z. The current from battery 272 65 through the windings of polar relay 210 causes the same to close its upper contact to initiate the operation of the mechanism at office Y. The closure of the contact of relay 370 establishes the energizing circuit for relay 327 which, in closing its contacts, prepares a circuit for relay 328 which operates to close its contacts at the termination of the first impulse. A circuit is then prepared for relay 325 as before and this relay, after an 70 interval, closes its alternate contact. The transmission of impulses being at this time under the sole control of the interrupter 105, relay 325 energizes before the second impulse is transmitted and therefore the ground connected to the contact of relay 370 which responds to the second impulse is extended through the alternate contact of relay 325 to energize the relay 337 and relay 316 is therefore prevented from operating. The relay 324 being energized, the energization of relay 337 establishes a circuit for relay 317 extending from grounded battery through the winding of this relay, the right-hand normal contacts of relays 367, 357 and 347 in series, 80 the right-hand alternate contact of relay 337, the alternate contact of relay 324 and the normal contact of relay 326. The operation of relay 327 causes the transmission of another impulse to office X to energize the 85 polar relay 110 thereat and relay 108 is then energized through the interrupter 104 to ground. Therefore, immediately upon the termination of the second impulse, another one is transmitted under the control of interrupter 104 and relays 337 and 338 being energized at this time, the ground connected to the contact of relay 370 is extended through the normal contact of relay 335 and the winding of relay 326 to the common battery at relay 365. The energization of relay 326 in this circuit, removes the locking ground from the right-hand winding of relay 324 and this relay with relay 315 thereupon release. The release of relay 315 removes the holding ground for relay 317 which thereupon releases. At the termination of the impulse, relay 326 releases and at this time relay 335 closes its alternate contact. The next succeeding impulses transmitted from office X are again under the sole control of the interrupter 105 and these impulses, upon reaching office Z, operate and restore the remaining groups of stepping relays in the series at said office in the same 100 manner as previously described. The impulses transmitted from office X in the opposite direction are repeated at office Y to operate the mechanism thereat and to effect the energization of the polar 105 relay 70 each time an impulse is received at office W. The first impulse received thereat energizes relay 27 and at the termination

of this impulse, relay 28 energizes to establish a circuit for relay 25. The impulses being under the sole control of interrupter 105 at this time, the relay 25 will operate 5 before the second impulse is received at office W and therefore the ground from the contact of relay 70 will be extended to energize the relay 37 whereupon this relay closes the energizing circuit for relay 38 10 which closes its contacts at the termination of the impulse. It is at this time that the transmission of an impulse from office X is under the control of the interrupter 104 and this impulse being received at office W immediately after the termination of the last impulse causes the energization of relay 26 through the normal contact of relay 35 which does not close its alternate contact until after the termination of the present impulse. Relay 26, upon energizing, establishes a circuit for relay 19 extending from ground through the alternate contact of relay 26 and the winding of relay 19 to the common battery at relay 65. Relay 19 20 energizes and establishes a circuit from the source of signaling current 73 through the left-hand alternate contact of relay 19, the ring contacts of jack 10 and plug 1, the lower normal contact of ringing key 3, the left-hand winding of relay 6, condenser 7, the upper normal contact of ringing key 3, the tip contacts of plug 1 and jack 10, and the right-hand alternate contact of relay 19 30 to the source of current 73. Relay 6 responds to the current flowing in this circuit and locks in a circuit extending from ground through the right-hand winding and upper contact of relay 6, the normal contact of listening key 4 and the contact or relay 2 to grounded battery. Relay 6, in energizing, 40 establishes a circuit for the supervisory lamp 5 extending from ground through the lamp 5, the lower contact of relay 6, the normal contact of listening key 4 and the contact of relay 2 to grounded battery. The operator at office W upon observing the lighted condition of lamp 5 removes the plug from jack 10 and thus terminates the call over the line A. The disconnection of this link circuit from the line A has no effect upon relays 11, 12 and 13 as the plugs of other link circuits are still engaged with jacks 20 and 30. The succeeding impulses transmitted from office X again being under the sole control of the interrupter 105, the remaining groups of all the stepping relays in the series at office W are operated in the same manner as previously described and at the termination of the operation thereof 50 are restored to normal, as before.

At the termination of the conversation over the phantom line B, the operator at office Z operates the ringing key 3 of the link circuit connected to jack 320 and there-

by energizes relay 334 through its left-hand winding in the same manner as described in connection with relay 324. The energization of relay 334 again establishes a circuit for relay 315 through the alternate contact of relay 334 and the normal contact of relay 336 to ground. Relay 315 in energizing, causes the operation of relay 317 which causes an impulse to be transmitted to office X through office Y in the same manner as before described to initiate the operation of the impulse mechanism at office X. In the present instance, the first three impulses to be transmitted from office X are under the sole control of the interrupter 105 and cause the operation of relays 327, 328, 325, 337, 338 and 335 without energizing relays 316 and 326. The third impulse energizes relay 347 and relay 334 being now energized, a circuit is established for relay 317 extending from grounded battery through the winding of said relay, the right-hand normal contacts of relays 367 and 357, the right-hand alternate contact of relay 334 and the normal contact of relay 336 to ground. Relay 317 again operates to transmit an impulse to office X which energizes polar relay 110 and under the control of interrupter 104, relay 108 is energized through its right-hand winding to transmit a fourth impulse immediately after the termination of the previous one. The energization of relay 347 establishes the energizing circuit for relay 348 and this relay closes its contacts at the termination of the third impulse and thereby establishes the circuit for relay 345 which, 100 however, does not close its alternate contact until after the termination of the fourth impulse. When this fourth impulse is received at office Z, the ground at the contact of polar relay 370 is extended through the normal contact of relay 345 and the winding of relay 336 to the common battery at relay 365. Relay 336 operates and removes the locking ground for relay 334 and also causes the release of relay 315. The opening of the alternate contact of relay 334 also releases relay 317. At the termination of the fourth impulse, relay 336 releases to open the circuits for relays 334, 315 and 317 and relay 345 closes its alternate contact so that succeeding impulses received at office Z under the control of interrupter 105 operate to cause the energization of the remaining stepping relays of the series at office Z and after the same are all operated, they are restored 110 to normal as previously described.

The first impulse transmitted from office X to office W under the sole control of interrupter 105 cause the energization of relays 27, 28, 25, 37, 38, 35, 47 and 48 in the same manner as previously described. It is at this time that relay 108 at office X operates under the control of interrupter 104 to trans-

mit another impulse which follows immediately after the termination of the third impulse and before relay 45 operates. The ground from polar relay 70 in response to 5 this fourth impulse is extended through the normal contact of relay 45 and the winding of relay 36 to battery at relay 65. Relay 36 energizes in this circuit and closes a circuit from ground through the alternate contact 10 thereof and the winding of relay 29 to battery at relay 65. Relay 29 energizes and through its alternate contacts connects the source of signaling current 73 through the left-hand winding of the relay 6 of the link 15 circuit connected to jack 20 in the same manner as just described in connection with the transmission of the disconnect signal over line A. The lamp 5 of the link circuit connected to line B is lighted and the operator 20 observing this condition, withdraws the plug of the link circuit from the jack 20. Relays 11, 12 and 13 remain in their operated condition due to the engagement of the plug of 25 another link circuit in jack 30. At the termination of the impulse, relay 45 closes its alternate contact and the remaining impulses again under the sole control of interrupter 105, operate to energize the remaining groups of stepping relays in the series at 30 office W and upon the operation of relay 65, the entire stepping mechanism is restored to normal as before. Again the stepping relays at offices X, Y and Y' operate as before but still have no effect upon the system. 35 Upon the termination of the conversation over line circuit C, the operator at office Z actuates the ringing key of the link circuit connected to jack 330 and causes the energization of relay 344, through its left-hand 40 winding. Relay 344 locks in a circuit including the winding of relay 315, and the normal contact of relay 346 and relay 315 energizes to cause the operation of relay 317. The battery 371 then transmits an impulse to office Y where the same is repeated as before to energize the polar relay 110 45 at office X with the result that the operation of the impulse sending mechanism thereat is again initiated. The impulses 50 transmitted from office X under the sole control of the interrupter 105 operate, at office Z, the relays 327, 328, 325, 337, 338, 335, 347, 348, 345, 357 and 358. Upon the energization of relay 357, a circuit is established for relay 317 extending from 55 grounded battery through the winding of said relay, the right-hand normal contact of relay 367, the alternate contact of relay 357, the alternate contact of relay 344 and the normal contact of relay 346 to ground. Relay 317 operates and causes the transmission of an impulse to office X to again energize the polar relay 110 which, in turn, 60 causes the energization of relay 108 under the control of the interrupter 104. At the 65 termination of the impulse which energizes relay 357, relay 358 energizes to establish a circuit for relay 355 but this relay does not close its alternate contact until after the impulse controlled by the interrupter 104 has 70 been received at office Z. Therefore, the ground at the contact of polar relay 370 is extended through the normal contact of relay 355 and the winding of relay 346 to the battery at relay 365. Relay 346 energizes in this circuit and removes the locking ground for relay 344 and also causes the release of relay 315 and the consequent release of relay 317. At the termination of 75 this impulse, relay 355 operates to open the energizing circuit for relay 346 which then restores. The succeeding impulse under the control of interrupter 105 causes the energization of relay 367 which establishes the circuit for relay 368 and this relay closes 80 its contacts upon the termination of this impulse. An obvious circuit is then established for relay 365 and after an interval 85 this relay opens its normal contact to release the stepping relays at office Z. 90

The transmission of impulses from office X to office W under the sole control of interrupter 105 in this instance, causes the operation of relays 27, 28, 25, 37, 38, 35, 47, 48, 45, 57 and 58. The impulse which energizes relay 57 is followed immediately by the impulse under the control of the interrupter 104 and relay 58 having energized at the termination of the first-mentioned 95 impulse and relay 55 being still in its normal condition, the ground at the contact of polar relay 70 is extended through the normal contact of relay 55 and the winding of relay 46 to the common battery at relay 65. Relay 46 energizes and closes a circuit extending from ground through the alternate contact thereof and the winding of relay 39 to the common battery at relay 65. Relay 39 operates and in closing its alternate 100 contact, connects the source of signaling current 73 through the left-hand winding of relay 6 of the link circuit connected to jack 30 to energize this latter relay and to cause the lighting of the lamp 5 of said link circuit in the same manner as in the other instances. At the termination of this 105 last impulse, relay 55 energizes and opens the energizing circuit for relay 46 which then restores. The succeeding impulse under the control of interrupter 105 causes the operation of relays 67, 68 and 65 and the operation of the latter relay disconnects the common battery to cause the release of the stepping relays at office W. As before, the stepping relays at office X, Y and Y' operate 110 in response to the impulses transmitted, but the operation thereof has no effect upon the system. 115

120

125

Operator at office W disconnects the link circuit from the jack of line circuit C.

- 5 The operator upon observing the lighted condition of lamp 5 of the link circuit connected to jack 30, removes the plug 1 of this link circuit from the jack and thereby opens the circuit for relay 11. In releasing, this
 10 relay causes the deenergization of relays 12 and 13 but relay 12 being slow to release, establishes a momentary circuit extending from ground through the alternate contact thereof, the left-hand winding of relay 54, and the normal contact of relay 13 to grounded battery. Relay 54 energizes and locks in a circuit from grounded battery, the winding of relay 15, the right-hand winding and alternate contact of relay 54
 15 and the contact of relay 56 to ground. Relay 54 energizes and locks in a circuit from grounded battery, the winding of relay 15, the right-hand winding and alternate contact of relay 54
 20 and the contact of relay 56 to ground. Relay 15 energizes in this circuit and establishes the previously described circuit for relay 17 through the normal contacts of relays 27, 37, 47, 57 and 67 in series. Relay 17
 25 energizes and completes the transmission of an initiating impulse to office X, in the same manner as previously described whereupon relay 103 is energized. This again initiates the operation of the impulse sending mechanism at office X and under the sole control of the interrupter 105, a series of impulses is transmitted to office W to operate the entire series of stepping relays thereat. Upon the energization of relay 67, a
 30 circuit is established for relay 17 extending from grounded battery through the winding of said relay, the left-hand alternate contact of relay 67, the contact of relay 54 and the contact of relay 56 to ground. Relay 17 operates to cause the transmission of an impulse from office W to office X in the same manner as before and upon the operation of the polar relay 100 and the engagement of a grounded segment of interrupter
 35 104, relay 108 is again energized through its right-hand winding to transmit an additional impulse. After the termination of the impulse which energizes relay 67 to close the energizing circuit for relay 68, this relay closes its contacts and establishes a circuit for relay 65. The next impulse received at office W is then extended through the left-hand contact of relay 68, the left-hand contact of relay 65 and the winding of relay 56 to the common battery at relay
 40 65. Relay 56 energizes and in opening its contact removes the locking ground for relay 54, opens the energizing circuits for relays 15 and 17 and these relays thereupon release.
 45 The transmission of impulses from office X to office Y during this last operation effects the successive operation of the stepping relays at the latter office in the same
 50 manner as previously described until the last impulse under the control of interrupter 105 has terminated. At this time, relay 242 is energized and has established a circuit for relay 243 but this relay, being slow to operate, does not open its contacts until
 55 after the last impulse has been transmitted which is under the control of the interrupter 104. This impulse operates the polar relay 210 as before to close its upper contact and a circuit is thereupon established from battery through the right-hand alternate contact of relay 242, the right-hand winding of relay 209, the middle alternate contact of relay 242, the right-hand contact of relay 243, the alternate contacts of relays 233, 223, 213 and 203 in series and the upper contact of polar relay 210 to ground. The windings of relay 209 being differential, the current flowing through this circuit causes the relay to release and removes the ground at the right-hand contact thereof which causes the restoration of the telephone repeaters at offices Y to normal. At the termination of the impulse controlled by interrupter 104, relay 243 opens its normal contacts and causes the release of the stepping relays at office Y in the same manner as before. The transmission of the impulses from office X
 60 operates the mechanism at office Y in the same manner as that described in connection with the operation at office Y and the telephone repeaters at office Y are also restored to normal.

At office X, the operation of relay 141 in response to the last impulse under the control of the interrupter 105 establishes the energizing circuit for relay 142. Relay 142 being slow to operate, does not close its alternate contacts until after the termination of the impulse controlled by interrupter 105. It is at this time that the next succeeding impulse is controlled by interrupter 104 and a circuit will now be established from ground through the interrupter 104, the contact of polar relay 100, the right-hand contact of relay 107, the junction point 113, the right-hand winding of relay 109 and the right-hand alternate contact of relay 142 to battery 143. Relay 109, being differential, is released by the current flowing through this circuit and the opening of its right-hand alternate contact disables the battery supply for the filaments of the telephone repeaters associated with the lines A, B and C at office X and these repeaters are then restored to normal. The energization of relay 142 disconnects the common battery supply 143 from the stepping relays at office X and these relays then restore. The apparatus at the various offices is now in its normal condition. It is believed that from the foregoing description the initiation of calls and the transmission of disconnect signals from of

65 70 75 80 85 90 95 100 105 110 115 120 125

The transmission of impulses from office X to office Y during this last operation effects the successive operation of the stepping relays at the latter office in the same

fice Z to office W will be readily understood.

What is claimed is:

1. In a telephone system, distant offices, a central office, a plurality of transmission lines interconnecting said offices, a signaling circuit connected to certain of said lines, and means at said central office operable when any one of said lines is taken for use to transmit a series of impulses over said signaling circuit to said distant offices to selectively determine at one of them the particular line over which a call is initiated. 70
2. In a telephone system, distant offices, a central office, a plurality of transmission lines interconnecting said offices, a signaling circuit connected to certain of said lines, means at said central office operable when a line is taken at one distant office to transmit a series of impulses over said signaling circuit to the other distant office to selectively determine at the latter office the particular line taken for use, a signal at the first named distant office, and means at said other distant office controlling the first named means to actuate the signal at said first named distant office. 75
3. In a telephone system, distant offices, a central office, a plurality of transmission lines interconnecting said offices, a signaling circuit connected to certain of said lines and an impulse sending mechanism at said central office operable when any one of said lines is taken for use to transmit a series of impulses over said signaling circuit to said distant offices to selectively determine at one of them the particular line over which a call is initiated. 80
4. In a telephone system, distant offices, a central office, a plurality of transmission lines interconnecting said offices, a signaling circuit connected to certain of said lines, and an impulse sending mechanism at said central office operable when one of said lines is taken for use to transmit a series of impulses over said signaling circuit to said distant offices, and to transmit another series of impulses thereto, modified with respect to the first series when a different line is taken for use. 85
5. In a telephone system, distant offices, intermediate telephone repeater offices, a central office, a plurality of transmission lines interconnecting the various offices, a signaling circuit connected to certain of said lines, an impulse sending mechanism at said central office operable to transmit two series of impulses over said signaling circuit, means at said intermediate offices responsive to the first series of impulses for rendering effective the telephone repeaters thereat, and means at said distant offices responsive to the second series of impulses for indicating the particular line over which a call is initiated. 90
6. In a telephone system, distant offices, intermediate telephone repeater offices, a plurality of transmission lines interconnecting said offices, a signaling circuit connected to certain of said lines, an impulse sending mechanism operable to transmit a plurality of series of impulses over said signaling circuit, means at said intermediate offices responsive to one of said series of impulses to render effective the telephone repeaters at said offices, and means at said distant offices responsive to a second series of impulses when one of said lines is taken for use and responsive to a third series of impulses when another line is taken for use, the third series of impulses being modified with respect to the second series. 95
7. In a telephone system, distant offices, intermediate telephone repeater offices, a plurality of transmission lines interconnecting said offices, a signaling circuit connected to certain of said lines, an impulse sending mechanism operable to transmit a plurality of series of impulses over said signaling circuit, means at said intermediate offices responsive to one of said series of impulses to render effective the telephone repeaters at said offices, and means at said distant offices responsive to a second series of impulses when one of said lines is taken for use and responsive to a third series of impulses when another line is taken for use, each of the said series of impulses being modified with respect to the other two. 100
8. In a telephone system, distant offices, a central office, physical and phantom transmission lines interconnecting said offices, a signaling circuit connected to said physical lines, and an impulse sending mechanism at said central office operable when any one of said lines is taken for use to transmit a series of impulses over said signaling circuit to said distant offices to selectively determine at one of them the particular line over which a call is initiated. 105
9. In a telephone system, distant offices, a central office, physical and phantom lines interconnecting said offices, a signaling circuit connected to said physical lines, and an impulse sending mechanism at said central office operable when one of said lines is taken for use to simultaneously transmit a series of impulses over said signaling circuit to said distant offices and to transmit another series of impulses thereto modified with respect to the first series when a different line is taken for use. 110
10. In a telephone system, distant offices, intermediate telephone repeater offices, a central office, physical and phantom lines interconnecting the various offices, a signaling circuit connected to said physical lines, an impulse sending mechanism at said central office operable to transmit two series of impulses over said signaling circuit, means at said intermediate offices responsive to the first series of impulses for rendering effective the telephone repeaters thereat, and means at said distant offices responsive to the second series of impulses for indicating the particular line over which a call is initiated. 115
11. In a telephone system, distant offices, intermediate telephone repeater offices, a central office, physical and phantom lines interconnecting the various offices, a signaling circuit connected to said physical lines, an impulse sending mechanism at said central office operable to transmit two series of impulses over said signaling circuit, means at said intermediate offices responsive to the first series of impulses for rendering effective the telephone repeaters thereat, and means at said distant offices responsive to the second series of impulses for indicating the particular line over which a call is initiated. 120
12. In a telephone system, distant offices, intermediate telephone repeater offices, a central office, physical and phantom lines interconnecting the various offices, a signaling circuit connected to said physical lines, an impulse sending mechanism at said central office operable to transmit two series of impulses over said signaling circuit, means at said intermediate offices responsive to the first series of impulses for rendering effective the telephone repeaters thereat, and means at said distant offices responsive to the second series of impulses for indicating the particular line over which a call is initiated. 125
13. In a telephone system, distant offices, intermediate telephone repeater offices, a central office, physical and phantom lines interconnecting the various offices, a signaling circuit connected to said physical lines, an impulse sending mechanism at said central office operable to transmit two series of impulses over said signaling circuit, means at said intermediate offices responsive to the first series of impulses for rendering effective the telephone repeaters thereat, and means at said distant offices responsive to the second series of impulses for indicating the particular line over which a call is initiated. 130

first series of impulses for rendering effective the telephone repeaters thereat, and means at said distant offices responsive to the second series of impulses for indicating the particular line over which a call is initiated.

11. In a telephone system, distant offices, a central office, a plurality of transmission lines interconnecting said offices, a signaling circuit connected to certain of said lines, an impulse sending mechanism at said central office operable when one of said lines is taken for use to transmit a series of impulses over said signaling circuit to said 50 distant offices, and to transmit another series of impulses thereto, modified with respect to the first series when a different line is taken for use, and interrupters associated with said impulse sending mechanism 55 for changing the characteristics of said series of impulses.

12. In a telephone system, distant offices, intermediate telephone repeater offices, a plurality of transmission lines interconnecting said offices, a signaling circuit connected to certain of said lines, an impulse sending mechanism operable to transmit a plurality of series of impulses over said signaling circuit, means at said intermediate offices responsive to one of said series of impulses to render effective the telephone repeaters at said offices, means at said distant offices responsive to a second series of impulses when one of said lines is taken for use and 60 responsive to a third series of impulses when another line is taken for use, each of the said series of impulses being modified with respect to the other two, and interrupters associated with said impulse sending mechanism 65 for changing the characteristics of said series of impulses.

13. In a telephone system, distant offices, a central office, a plurality of transmission lines interconnecting said offices, a signaling circuit associated with said lines, and interrupter mechanisms at the central office operable when one of said lines is taken for use to transmit a series of impulses over said 70

signaling circuit to said distant offices to identify at one of them the particular line taken for use, a portion of said series of impulses being under the joint control of said interrupter mechanisms and the remaining portion of said series under the sole control of one of said interrupter mechanisms. 75

14. In a signaling system, distant offices, a central office, a plurality of transmission lines interconnecting said offices, a signaling circuit common to said lines, and an impulse sending mechanism at said central office operable when any one of said lines is taken for use to transmit a series of impulses over said signaling circuit to said distant offices to selectively determine at one of them the particular line over which a call is initiated. 80 85

15. In a signaling system, distant offices, intermediate telephone repeater offices, a central office, a plurality of transmission lines interconnecting the various offices, a signaling circuit common to said lines, an impulse sending mechanism at said central office operable to transmit two series of impulses over said signaling circuit, means at said intermediate offices responsive to the first series of impulses for rendering effective the telephone repeaters at said intermediate offices, and means at said distant offices responsive to the second series of impulses for indicating the particular line over which a call is initiated. 90 95

16. In a signaling system, an intermediate office, other offices, repeaters at said other offices, and means at said intermediate office for simultaneously controlling the repeaters at said other offices. 80

17. The method which comprises transmitting a series of impulses from a central point to distant points when a transmission line is taken for use to operate telephone repeaters, and transmitting another series of impulses to identify said line. 90

In witness whereof, I hereunto subscribe my name this 27th day of December, A. D. 1919.

ROY D. CONWAY.
